N. KOHLER,
SAFETY DEVICE FOR ELEVATORS,
APPLICATION FILED DEC. 6, 1918.

1,310,993.

Patented July 22, 1919.

UNITED STATES PATENT OFFICE.

NATHAN KOHLER, OF NEW YORK, N. Y., ASSIGNOR OF ONE-HALF TO NICHOLAS F. BADER, OF NEW YORK, N. Y.

SAFETY DEVICE FOR ELEVATORS.

1,310,993.

Specification of Letters Patent. Patented July 22, 1919.

Application filed December 6, 1918. Serial No. 265,478.

To all whom it may concern:

Be it known that I, NATHAN KOHLER, a citizen of the United States, and a resident of the city, county, and State of New York, have invented certain new and useful Improvements in Safety Devices for Elevators, of which the following is a specification.

My invention relates to safety devices for elevators. The object of the invention is to provide a simple and effective device for preventing elevators from falling in the event that the elevator supporting cables break or become so slack as to improperly support the elevator. The device is normally inactive or inoperative but upon breakage of a cable it goes into operation as soon as the break occurs and before the elevator falls any great distance or acquires dangerous momentum. The present device is not intended to stop the elevator suddenly at the position the elevator is in at the moment a cable breaks but it is intended to allow it to descend to the bottom of the shaft or some other point suitable for the discharge of the passengers, the elevator in this case descending by its own gravity but retarded by the present device. Inasmuch as the present device is inactive while the elevator is properly working there is no interference with the operation of the latter.

In the drawing forming part of this application,

Figure 1 is a front elevation of the upper portion of an elevator and its guides, with my invention applied thereto,

Fig. 2 is a plan view of the present device with parts shown in section,

Fig. 3 is a face view of the stationary portion of the retarding device,

Fig. 4 is a sectional view taken on the line 4—4 of Fig. 3 and showing the roller in operation,

Fig. 5 is a side elevation of parts of the device,

Fig. 6 is a detail view of certain parts,

Fig. 7 is a sectional view showing the toggle connection at the cable, and

Fig. 8 is a sectional view of a spring device for resisting the oscillations of the plunger.

In the drawing I have shown the upper portion 1 of an elevator and it is to be understood that the present invention may be used on any kind or form of elevator. I

have also shown guides or ways 2 which latter will extend vertically in the elevator shaft at each side of the elevator and co-extensively with the path of the elevator.

I have provided at each side of the elevator stationary guides, tracks, or retarding means, here shown as upright metal bars 3, 4 secured to the ways 2 by bolts 5. These bars 3, 4 have their opposed edges curved or serrated at 6 so that the space between these edges forms a groove 7 which zig-zags back and forth in relation to a perpendicular line. Preferably, the groove 7 is formed with equal and regular reverse curves 8 as shown, the peaks of the curves at each side being equidistant from a line drawn vertically through the groove. The retarding device on the elevator co-operates with this groove, but normally, or when the elevator is properly operating, there is no engagement between the device on the elevator and the guide.

I have shown two retarding devices, one at each side of the elevator, one of which may be connected with the cable which runs to the winding drum (not shown) and the other of which may be connected to the cable which runs to the usual counterweight (not shown). In this way the elevator is protected against breakage of either cable. These devices are constructed and operate alike so that a description of one will answer for both.

There is a base 9 firmly secured to the frame of the elevator by bolts 10 or other securing means. There is a plunger 11 adapted to slide on this base 9 and its movement laterally is limited by means of a strap 12 which extends over the top of the plunger and is secured to the base. The plunger is thus inclosed in a rectangular pocket by the base 9 and strap 12 with only sufficient vertical play of the plunger therein to permit of freedom of movement, whereas, the pocket is wider than the plunger in order to permit the latter to oscillate laterally. The free end of the plunger section 13 projects outwardly at one side of the elevator so that it is in line with the guiding bars 3, 4. Preferably, this free end is provided with a roller 14 to reduce friction and binding when the plunger engages the guide bars.

The plunger is made in two sections, the

section 13, previously described, and the section 15 which extends through a bearing formed by the base 9 and a strap 16 and the section 15 is partially guided by a bolt 17 passing through a slot 18 and secured in the base 9. The sections 13 and 15 are connected by an articulate connection, preferably consisting of the overlapping ears 19, 20 on the respective sections 13, 15 through 10 which passes a hinge pin 21. The purpose of this form of connection is to permit the section 13 to oscillate in relation to the section 15 with the pin 21 as the pivotal point.

There is a compression spring 22 surrounding the plunger section 15 and compressed between the strap 16 and the enlargement 23 of the plunger, the purpose of which spring is to force the plunger outwardly and toward the guide bars.

20 The inner end of the plunger section 15 has a fork 24 which straddles the links 25, 26, which are pivoted, respectively, to the end of the cable at 27 and to the elevator at 28 and the links and fork are pivotally 25 connected by a pin 29. This constitutes a toggle connection between the plunger and the cable.

The parts described above will in themselves serve to a certain extent to accomplish the object intended, but I prefer to provide means for resisting the lateral oscillations of the plunger to further retard the movement of the elevator. I have shown in Figs. 2, 5 and 6 a cylinder 30 fixed 30 to an extension of the base 9. There is a piston 31 sliding in this cylinder and in a direction at right angles to the plunger. The spindle 32 of the piston passes through stuffing boxes 33, 34, in the heads 35 of the cylinder and one end of the spindle is connected with the plunger section 13. I have shown a slotted extension 36 on one side of the plunger section 13 and the fork 37 on the end of the spindle 32 straddles this extension 40 and there is an anti-friction roller 38 carried by the pin 39 in the fork, the roller 38 traveling in the slot in the extension 36. The cylinder 30 may be filled with any fluid. It may be air or liquid, preferably the latter. 45 There is a by-pass port 40 connecting the opposite ends of the cylinder, so that the fluid in the cylinder will be transferred from one side of the piston to the other, back and forth through the by-pass. The 50 check valve 41 is adapted to regulate the by-pass to check the movement of the fluid to suit requirements and thus regulate the resistance to the lateral movement of the plunger 13.

60 Operation: Assuming that there is a protective device at each side of the elevator, and that each is connected to a different cable either one or both may become op-

erative. They both operate alike so that a description of one will suffice for both. 65 As long as the elevator and its cables are in proper condition each cable is under sufficient tension to hold it taut and the toggle links 25, 26 will be held vertically as shown, 70 since the tension of the cable tends to keep them in this position. So long as this condition exists, the plunger is held in retracted position, free of the guide bars 3, 4 and partaking of no movement other than that of traveling with the elevator. If the 75 cable breaks or becomes slack so that it no longer properly supports the elevator, the spring 22 which is always exerting its force to project the plunger, will cause the toggle to bend and it will force the plunger lengthwise and toward the nearest guide bars 3, 4. The end of the plunger carrying the roller 14 will be projected into the guiding grooves 7 either immediately or as soon as it comes 80 into line with a portion of the groove, which, 85 in any case, will occur when the elevator has moved not more than the distance from one curve in the groove to the next one. As soon as the roller 14 enters the groove 7 it will be compelled to follow the zig-zag 90 course thereof as the elevator descends. This will cause the plunger section 13 to oscillate from the pin 21 as its center and the lateral movement is transmitted from the plunger through the spindle 32 to the piston 31. At 95 each reciprocation of the piston the fluid in the cylinder is transferred from one side to the other of the piston through the by-pass 40 and the flow of the fluid is sufficiently restricted to resist the movement of the piston, and thus the oscillations of the plunger are opposed. As the plunger is compelled to follow the course of the groove 7 it must displace the fluid in the cylinder back 100 and forth. The valve 41 may be regulated to permit the elevator to descend at any desired speed. As the safety device is not intended to stop the elevator but only to hold its speed within reasonable limits there is no dangerous strain on the safety device or 110 the elevator. The support of the elevator is simply transferred from the cable to the safety device and the elevator continues to descend under the control of the latter. In many instances the passengers may not even 115 be aware of any defect in the operation of the elevator.

I prefer the fluid device for resisting the plunger as it is smooth and as it is adapted for varying loads. In Fig. 8 I have shown, 120 however, how buffer springs 42, 43 arranged in the cylinder and on opposite sides of the piston, may be substituted for the fluid. As the piston reciprocates these springs are alternately compressed and this offers resistance to the oscillations of the plunger. 125

The present device is very simple and effective and it in no way interferes with the normal operation of the elevator.

Having described my invention, what I claim is:

1. The combination of an elevator and a safety device therefor, comprising a stationary guide arranged near the path of the elevator and having a zig-zag groove, a plunger carried by the elevator and normally held out of operative relation with said guide by the elevator cable, means for projecting said plunger into said groove, said plunger being adapted to move laterally to follow the course of said groove as the elevator descends, and resisting means for opposing the lateral movement of said plunger for the purpose set forth.

2. The combination with an elevator having a cable and a safety device therefor,

comprising a stationary guide having a zig-zag groove, a plunger mounted on the elevator, said plunger comprising pivoted sections, means for confining one section to a rectilinear movement, means for confining the other section to rectilinear and lateral oscillatory movements, said latter section being adapted to engage said guide groove and to be oscillated thereby, resisting means for opposing said oscillations, a spring for projecting said plunger into engagement with said groove, and a pair of links by which the elevator cable is connected with the elevator, said links being fulcrumed to said plunger whereby when the cable is taut the plunger will be held out of operative relation with said guide.

Signed at the city, county and State of New York, this 16th day of October, 1918.

NATHAN KOHLER.
